US00D663320S

(12) **United States Design Patent**
Akana et al.

(10) **Patent No.:** **US D663,320 S**
(45) **Date of Patent:** **** Jul. 10, 2012**

(54) **ELECTRONIC DEVICE WITH GRAPHICAL
USER INTERFACE**

(75) Inventors: **Jody Akana**, San Francisco, CA (US); **Bartley K. Andre**, Menlo Park, CA (US); **Jeremy Bataillou**, San Francisco, CA (US); **Daniel J. Coster**, San Francisco, CA (US); **Anton Davydov**, Gilroy, CA (US); **Daniele De Iuliis**, San Francisco, CA (US); **Jorge Fino**, San Francisco, CA (US); **Evans Hankey**, San Francisco, CA (US); **Richard P. Howarth**, San Francisco, CA (US); **Jonathan P. Ive**, San Francisco, CA (US); **Duncan Robert Kerr**, San Francisco, CA (US); **Shin Nishibori**, Portola Valley, CA (US); **Matthew Dean Rohrbach**, San Francisco, CA (US); **Peter Russell-Clarke**, San Francisco, CA (US); **Christopher J. Stringer**, Woodside, CA (US); **Eugene Antony Whang**, San Francisco, CA (US); **Policarpo Wood**, San Francisco, CA (US); **Rico Zorkendorfer**, San Francisco, CA (US)

(73) Assignee: **Apple Inc.**, Cupertino, CA (US)

(**) Term: **14 Years**

(21) Appl. No.: **29/401,912**

(22) Filed: **Sep. 16, 2011**

Related U.S. Application Data

(63) Continuation of application No. 29/368,991, filed on Aug. 31, 2010, now Pat. No. Des. 647,919, which is a continuation of application No. 29/367,996, filed on Aug. 16, 2010, now Pat. No. Des. 638,030.

(57) **CLAIM**

The ornamental design for an electronic device with graphical user interface, as shown and described.

DESCRIPTION

FIG. 1 is a front bottom perspective view of an electronic device with graphical user interface showing our new design; FIG. 2 is a rear bottom perspective view thereof; FIG. 3 is a rear top perspective view thereof; FIG. 4 is a front top perspective view thereof; FIG. 5 is a front view thereof; FIG. 6 is a rear view thereof; FIG. 7 is a bottom view thereof; FIG. 8 is a top view thereof; FIG. 9 is a side view thereof; and, FIG. 10 is another side view thereof.

The broken lines showing portions of the electronic device and portions of the graphical user interface form no part of the claimed design.

UNITED STATES PATENT AND TRADEMARK OFFICE
CERTIFICATE OF CORRECTION

PATENT NO. : D663,320 S
APPLICATION NO. : 29/401912
DATED : July 10, 2012
INVENTOR(S) : Jody Akana

Page 1 of 1

It is certified that error appears in the above-identified patent and that said Letters Patent is hereby corrected as shown below:

Title Page, item (75), inventors, please change “Bartley K. Andre, Menlo Park, CA (US)” to
-- Bartley K. Andre, Palo Alto, CA (US) --.

Title Page, item (75), inventors, please change “Jorge Fino, San Francisco, CA (US)” to
-- Jorge Fino, San Jose, CA (US) --.

Title Page, item (75), inventors, please change “Shin Nishibori, Portola Valley, CA (US)” to
-- Shin Nishibori, Kailua, HI (US) --.

Title Page, item (75), inventors, please change “Policarpo Wood, San Francisco, CA (US)” to
-- Policarpo Wood, San Jose, CA (US) --.

Title Page, item (75), inventors, please change “Rico Zorkendorfer, San Francisco, CA (US)” to
-- Rico Zörkendörfer, San Francisco, CA (US) --.

Signed and Sealed this
Eighth Day of October, 2013

Teresa Stanek Rea
Deputy Director of the United States Patent and Trademark Office
